(57) CLAIM

The ornamental design for a travel blanket with integrated case and luggage strap, as shown and described.

DESCRIPTION

FIG. 1 is a perspective view of a travel blanket with integrated case and luggage strap showing my new design;

FIG. 2 is a front plan view thereof;

FIG. 3 is a rear plan view thereof;

FIG. 4 is a left-side plan view thereof;

FIG. 5 is a right-side plan view thereof;

FIG. 6 is a top plan view thereof; and,

FIG. 7 is a bottom plan view thereof.

The broken line showing environment is for illustrative purposes only and forms no part of the claimed design.
